US0D1101633S

(12) **United States Design Patent** (10) **Patent No.:** **US D1,101,633 S**
(45) **Date of Patent:** **** Nov. 11, 2025**

(54) **SUSPENSION LINKAGE**

(71) Applicant: **Shenzhen Wins Sport Technology Co., Ltd.**, Shenzhen (CN)

(72) Inventor: **Shengfei Zhao**, Guangdong (CN)

(73) Assignee: **Shenzhen Wins Sport Technology Co., Ltd.**, Guangdong (CN)

(**) Term: **15 Years**

(21) Appl. No.: **29/960,363**

(22) Filed: **Aug. 29, 2024**

(51) LOC (15) Cl. **12-11**

(52) U.S. Cl.

USPC **D12/111**

(58) **Field of Classification Search**

USPC D12/111, 117, 412, 414, 419;

D21/423-428, 431-435

CPC B62K 3/00; B62K 3/02; B62K 3/06

(57) **CLAIM**

The ornamental design for a suspension linkage as shown and described.

DESCRIPTION

FIG. 1 is a top, front and left perspective view of a suspension linkage showing my new design;
FIG. 2 is a bottom, rear and right perspective view;
FIG. 3 is a front elevational view thereof;
FIG. 4 is a rear elevational view thereof;
FIG. 5 is a left view thereof;
FIG. 6 is a right view thereof.
FIG. 7 is a top plan view thereof; and,
FIG. 8 is a bottom plan view thereof.
